UNITED STATES PATENT OFFICE.

DAVID D. DAILEY, OF ATMORE, ALABAMA.

DEVICE FOR DESTROYING BOLL-WEEVIL MOTHS.

1,341,706.

Specification of Letters Patent.

Patented June 1, 1920.

Application filed February 28, 1918, Serial No. 219,709. Renewed April 3, 1920. Serial No. 371,144.

To all whom it may concern:

Be it known that I, DAVID D. DAILEY, a citizen of the United States, residing at Atmore, in the county of Escambia, State 5 of Alabama, have invented a new and useful Device for Destroying Boll-Weevil Moths; and I do hereby declare the following to be a full, clear, and exact description of the invention, such as will enable others skilled 10 in the art to which it appertains to make and use the same.

The present invention relates to a device for catching and destroying boll weevil moths, and has for its object to provide a 15 device of this character which embodies novel features of construction whereby large quantities of the moths can be destroyed, thereby preventing them from boring into the cotton bolls and depositing the eggs 20 which result in the destructive boll weevils.

Further objects of the invention are to provide a device of this character which can be used to advantage in any cotton field, which does not interfere in any manner 25 with planting or cultivating the cotton and does not necessitate the use of poisonous solutions, and which is quite effective in catching and destroying the boll weevil moths.

With these and other objects in view, the invention consists in certain novel combinations and arrangements of the parts as will more fully appear as the description proceeds, the novel features thereof being 35 pointed out in the appended claims.

For a full understanding of the invention, reference is to be had to the following description and accompanying drawing, in which:—

Figure 1 is a side elevation of a boll weevil exterminating device constructed in accordance with the invention, portions being broken away and shown in section.

Fig. 2 is a similar view with the bag in 45 position over the device.

Fig. 3 is a sectional view through the bag and the pan to which the bag is applied after being removed from the post structure.

Fig. 4 is a top plan view of the pan.

Corresponding and like parts are referred to in the following description and indicated in all the views of the drawings by the same reference characters.

Referring to the drawings, which illustrate one embodiment of the invention, the numeral 1 designates a standard which is

adapted to be driven into the ground at a convenient position in the cotton field, said standard being provided at opposite sides thereof with notches 2 which have horizontal upper sides and undercut lower sides. Shelves 3 project horizontally in opposite directions from the sides of the standard 1, the inner ends of the shelves projecting loosely within the notches 2 and the said 65 shelves being secured to the edges of the standard 1 at the mouths of the respective notches by means of hinges 4. The inner ends of the shelves which project within the notches 2 normally abut against the horizontal upper sides of the notches to hold the shelves in a horizontal position, although they can be swung downwardly into the undercut lower portions of the notches to permit a limited rocking or agitation of the 70 shelves. A quantity of hay 5 is placed upon each of the shelves 3 and permitted to remain thereon, since it has been discovered that the cotton boll weevil moths which 75 come to the field during the night will be attracted by the hay and will in most instances be found concealed in the hay at morning.

These devices will be distributed throughout the cotton field, and each morning an attendant will visit them and collect the moths in a sack. For this purpose, the sack, such as that shown at 6, may be inverted and placed over the standard and shelves, and the shelves then agitated to dislodge the 80 moths from the hay and cause them to gather in the sack. For the purpose of agitating the shelves a vertical plunger 7 is shown as slidably mounted within the longitudinal bore 8 of the standard, and being 85 provided at its upper end with a suitable finger piece 9. A series of arms 10 project laterally from the plunger 7 and loosely engage eyes 11 at the inner ends of the shelves 3. With this construction it will be 90 obvious that by successively pressing downwardly upon the plunger and then releasing it the shelves can be agitated to dislodge the moths from the hay 5, whereupon they collect in the top of the sack and remain in 95 the sack when it is lifted from the standard. These moths are destroyed by dumping them into a pan 12 which is partially filled with crude oil 13. This pan may be provided with a bail 14 for convenience in carrying 100 it from place to place, and may also be provided at its edges with hooks 15 for engag-

ing the mouth of the inverted sack 6. After the sack has thus been applied to the pan the moths can be forced down into the crude oil which kills them very quickly. By the 5 use of this device large numbers of the moths can be collected and killed, and this will very greatly reduce the damage which would be done to the crop by the boll weevils, since the moths are destroyed before they 10 have an opportunity to lay the eggs which would hatch into the boll weevils.

Having thus described the invention, what I claim as new and desire to secure by Letters Patent, is:—

- 15 1. A device for catching boll weevil moths, including a standard, a hay supporting shelf projecting from the standard, means for agitating the hay supporting shelf, and a sack adapted to be inverted over the standard 20 and shelf to collect the moths.
2. A device for catching boll weevil moths, including a standard, a hay supporting shelf projecting from the standard, a plunger mounted upon the standard and operatively 25 connected to the shelf for agitating the latter, and a sack adapted to be inverted over the standard and shelf to collect the moths therein.
3. A device for catching boll weevil moths, 30 including a standard, a series of hay supporting shelves projecting horizontally from

the standard and loosely connected thereto, a plunger slidably mounted upon the standard, arms projecting laterally from the plunger and operatively connected to the 35 shelves for agitating the latter, and a sack adapted to be inverted over the standards and shelves for collecting the moths.

4. A device for catching boll weevil moths, including a standard having notches in the 40 edges thereof, a series of hay supporting shelves projecting horizontally from the standard and having the inner ends thereof loosely received within the notches, hinges connecting the shelves to the standards at 45 the mouths of the notches, eyes at the inner ends of the shelves, a plunger slidably mounted upon the standard, arms projecting laterally from the plunger and loosely received within the eyes of the shelves for 50 agitating the shelves when the plunger is operated, and a sack adapted to be inverted over the standard and shelves to collect the moths.

In testimony whereof I have signed my 55 name to this specification in the presence of two subscribing witnesses.

D. D. DAILEY.
